UNITED STATES PATENT OFFICE.

FREDRICK B. THOMPSON, OF CHICAGO, ILLINOIS.

FILM-TREATING APPARATUS.

1,328,464.

Specification of Letters Patent. Patented Jan. 20, 1920.

Application filed August 16, 1915. Serial No. 45,846.

To all whom it may concern:

Be it known that I, FREDRICK B. THOMPSON, citizen of the United States, residing at Chicago, in the county of Cook and State 5 of Illinois, have invented certain new and useful Improvements in Film-Treating Apparatus; and I do hereby declare the following to be a full, clear, and exact description of the invention, such as will enable 10 others skilled in the art to which it appertains to make and use the same.

This invention has for its object to provide an apparatus for treating photographic film tape such as is used in the taking and projection of motion pictures, and relates particularly to certain specific improvements over the construction shown 15 and described in my application for Letters Patent Ser. No. 876030, filed December 20 8, 1914.

The main object of the present invention is to provide an apparatus of the kind specified in which the film is so carried and subjected to the action of the developing 25 and fixing liquids, water and fire-proofing compounds, coloring solutions, etc., that both faces thereof are equally exposed to such action, and in which the continuous traveling carrier for such film tape is so 30 geared to its actuating mechanism as to prevent any possibility of relative slippage or entanglement of such carrier and the film and which, furthermore, is so constructed and arranged as to maintain the film under 35 the predetermined tension at which it is fed to the carrier preparatory to subjecting the same to the action of such liquids and the like.

A further object of the invention is to 40 provide apparatus of the character defined in which all shrinkage in the film due to drying thereof after being subjected to the liquids for developing and fixing the same may be automatically compensated for in 45 the carrier at such points as may be necessary to prevent a buckling of the carrier by reason of the shortening of the film due to such shrinkage.

A further object of the invention is to 50 provide film treating apparatus of the character set forth in which the film after being subjected to the liquids as aforesaid, and before passing into the drying chamber, is wiped to remove all surplus moisture therefrom, whereby spotting thereof is prevented.

The invention may obviously be variously embodied and in the accompanying drawings I have illustrated only a preferred embodiment thereof.

60

In said drawings.

Figure —1— is a vertical longitudinal section through that portion of the apparatus in which the film is subjected to the action of liquids.

65

Fig. —2— is a plan of the drying chamber.

Fig. —3— is a fragmentary detail vertical section showing a sprocket and carrier chain employed, taken on the line 3—3 of 70 Fig. —4—.

Fig. —4— is a detail section on the line 4—4 of Fig. 3.

Fig. —5— is a detail section of an idle roll or sprocket employed.

75

Fig. —6— is a plan view of a slightly modified form of construction.

Fig. —7— is an enlarged detail section on the line 7—7 of Fig. —6—.

My invention consists essentially in providing as a carrier for the film tape an articulate structure which is in some respects similar to a sprocket chain, but differs in details of construction from such chains to adapt the same particularly to the purposes 85 and functions to be performed, such articulate structure being particularly advantageous in that it permits all parts of both faces of the film tape to be equally exposed to the action of liquids and to drying fluids 90 whereby the same is more uniformly and quickly treated than would otherwise be the case. This articulate structure is also very advantageous in that it permits the use in conjunction therewith of sprocket- 95

wheels, or the like positively engaged therewith to prevent slippage or lost motion between the carrier and said driving mechanism, and in that it also permits of the use of such sprocket wheels or the like, engaging said chain, the surfaces of which have grooves of such depth as to cause the parts of the chain engaged therewith and which engage the film tape to become completely embedded therein to a depth causing the 105 film tape to ride free of the carrier over the surfaces of said sprocket wheels thereby preventing a tension being imparted to the film tape due to the shortening of the spaces separating the film tape carrying bars of 110 the chain as the latter passes over successive sprockets, whereby an insufficient length of

film will be fed to correspond with the length of the chain on which the same rests, such shortening reacting on the carrier to buckle the latter.

5 The materials used in the construction of the apparatus and of the carrier are such as are not effected by the chemicals used for treating the film, this being obviously necessary and requisite to the successful use of the apparatus for the purpose intended.

10 The apparatus comprises a suitable supporting frame for the bearings 1 of the shafts 2 equipped with sprockets 3 over which the sprocket chain 4, constructed in accordance with my invention, is adapted 15 to be trained; each of said shafts preferably carrying a plurality of such sprockets, or having a plurality of sprocket faces which would constitute the equivalent of a 20 plurality of such wheels. The sprockets are maintained rigid with the shafts 2 in any suitable manner, and each of said shafts is further provided with a pair of sprockets 5 over which the driving sprocket-chains 6 25 are trained. Said shafts 2 are horizontally disposed and are parallel with each other and associated with each thereof is a plurality of free drums or spools 7 which are supported in the loops formed by the portions 30 of the sprocket chains depending from the said sprockets 3. The said sprockets 7 are removable at will and are preferably rendered relatively heavy so as to maintain the sprocket chain under a constant 35 tension, whereby to insure engagement of the cross-bars thereof in the grooves on the sprocket wheels 3 to prevent relative slippage of said parts, and also imparting sufficient tension on the film tape to overcome any slight resistance to the feed 40 thereof upon the carrier from a spool or reel.

As indicated in Fig. 1 the sprocket chain 4, of relatively great length and which is 45 endless, is first passed over a sprocket 3 on an idle shaft 8 at one end of the apparatus and passes downwardly over one of said spools or drums 7, thence upwardly over the next contiguous sprocket 3 on the same 50 shaft, whence it passes over the sprocket 3 at the contiguous end of the next contiguous shaft 2, thence in the reverse direction over the several sprockets on said shaft, alternating with said spools or drums 7, and then 55 zigzag from shaft to shaft successively until it reaches the other end of this portion of the apparatus, said chain passing alternately over the sprockets on all of said shafts and over the said idle drums on spools 7 associated therewith.

60 At the last-named end of the apparatus said sprocket chain passes over an idle sprocket 9 and thence over a guideway 10 above the several shafts 2 back to the first 65 sprocket of the idle shaft 8. Here it is

trained under one of the sprockets on shaft 8 and is then trained over an idle roll or spool 10^a of larger diameter rotatably mounted on a shaft 10^b above the shaft 8. The said sprocket chain travels continuously, said shafts 2 being motor driven and geared together by means of the sprockets 5 and sprocket chains 6 to rotate at uniform speed at all times.

70 Associated with the several shafts 2 are tanks 11 to 20 inclusive, for example, through all of which the chain travels successively, the duration of its travel through any one of said tanks being regulated by the number of sprockets 3 and companion 80 spools or drums 7 associated with the tank. The number of said sprockets may obviously be increased at will to secure the best results in the treatment of the film. The relative arrangement and connection of the 85 several tanks with each other is as follows:

75 The tank 11 is adapted to contain a film developing liquid and is equipped with a water jacket 22. The latter is connected at its upper end with a source of supply of cold 90 water, such as the service pipes of a building, and at its upper end by means of a pipe, with the lower end of the tank 20. This is in turn connected by means of an over-flow pipe with the next succeeding tank 95 19, and similar connections are made successively between the tanks 19 and 18; 18 and 17, etc., to the tank 15, which is similarly connected with the tank 12. From the upper end of the latter the water overflows into the sewer or other drain. The tanks 20 to 15 inclusive and the tank 12 are rinsing or washing tanks and the tanks 13 and 14 are "fixing" tanks containing a photographic fixing solution such as hypo-sulfite 100 of soda.

105 Thus the rinsing water flows in a general direction opposite to the direction of travel of the film tape thereby causing the latter to first pass through that portion of the rinsing water containing the greatest percentage of fixing solution and finally through the tank or tanks containing water entirely free of the same.

110 The said tanks are arranged in two groups, the first of which comprises the tanks 11, 12, and 13 and the other the remainder thereof, said tanks of each group being disposed so that their opposed walls contact with each other and are held firmly 115 in this relation by means of the cross-bars 25 and bolts 26, the said cross-bars reinforcing and preventing bulging of the flat walls of said tanks while the close contact of the opposed walls of contiguous tanks with each 120 other obviously prevents bulging of the same by equalization of pressure on opposite faces of the same, thus enabling the use of very much lighter material in the construction of said tanks than would otherwise be possible. 125

This arrangement also materially reduces the radiating surface of the tanks thereby maintaining the liquids contained therein at a more uniform temperature at all times.

- 5 The said groups of tanks are separated from each other by a space and may be segregated from each other by a fixed partition wall 21, and a suitable removable partition wall 27 such as a drop curtain or the
 10 like. Thus the group comprising the tanks 11, 12 and 13 may be disposed in a dark room and the other group in a well-lighted room, the film being so far fixed by passage through the fixing liquid contained in the
 15 tank 13, as to be immune to injury by exposure to daylight or other bright light after leaving the same and passing into the well-lighted space in which the tank 14, also containing such fixing solution, is situated.
 20 This arrangement is very advantageous, as will be obvious, as it enables the film to be closely inspected and watched during the remainder of its travel through the apparatus without strain on the eyes of the operator, and this holds true also of the carrier and all of the operating mechanism.

The film tape is adapted to be connected at one end with one of the cross-bars of the chain 4 by any suitable means, but preferably I provide for this purpose the device shown in detail in Fig. —3— which will be hereinafter more particularly described. The film thus attached to the carrier is unwound from its reel at uniform speed and
 35 is then passed continuously successively through the several tanks and is then detached from said sprocket chain 4 and attached to a second sprocket chain 28 by means of which it is carried through the
 40 drier. Before being attached to the second chain, however, the film is trained by the operator over wiping reels interposed between the developing and fixing portion of the apparatus and the drier; the said wiping
 45 means being particularly described and claimed in a copending application filed of even date herewith, Ser. No. 45845. The relative construction and arrangement of the shafts and sprockets over which the
 50 chain 28 is trained in the drier is identical with the same arrangement in the developing and fixing portion of the apparatus; said carrier mechanism on which the film is carried for the purpose of drying the same
 55 being housed in a suitable compartment 29 which is preferably heated and equipped with means for effecting forced passage of air therethrough and to impinge upon the film tape to promote drying of the latter to
 60 the end that the same may be delivered from said apparatus perfectly dry and ready for use.

The said sprocket chain 4 consists of links 30 each consisting of a short flat piece of metal and alternating therewith are sub-

stantially triangular links 31; the bases of which are slightly convex. The pins or rivets 32 connecting the links 30 and 31 pass through the end portions of the former and through the corners of the latter contiguous 70 to the bases thereof; said pins or rivets 32 being short, that is to say, of just sufficient length to pass through the several thicknesses of metal which they connect, and the openings through which the same pass are 75 preferably sufficiently large to provide a very free relative pivotal movement of said links 30 and 31 and also permitting distortion of the chain to a limited extent. The triangular links 31 are arranged in pairs, 80 each pair thereof being connected by means of a cross-bar 33 which passes through the base portions thereof at a point below the plane of the pivotal connections thereof with the links 30 so that when the chain is 85 straightened out a plane intersecting the axes of several of said cross-bars 33 will be parallel with but separated from a plane intersecting the axes of the several rivets or pins 32 connecting the said links 31 with the 90 links 30, the last-named planes being disposed nearer the apexes of said links 31, and the apex portions of the latter being adapted to project outwardly from the sprockets 3 and 7 over which said chain is trained. 95 The latter is made preferably of Monel metal which is known to be proof against the chemicals usually employed in developing and fixing photographic emulsions, though any other metal or material similarly adapted to the same purpose may obviously be substituted without departing from the invention.

Each of the sprockets 3 consists preferably of a drum, the face of which is provided with parallel annular grooves 34 bordering the longitudinally grooved surfaces 35, the longitudinal grooves 36 of the latter being adapted to receive the said cross-bars 33 of the chain. The said links 30 and 31 105 are adapted to be received within the said grooves 34 and supported, or practically supported, upon the ends of the bars 33 engaged in the grooves 36 as the chain travels over the said sprockets. Each of the grooves 110 36 is of a depth greater than the diameter of the cross-bars 33 so that the latter will become disposed inwardly of the convex surfaces 35 and the latter thus brought in contact with the film tape to carry the latter out 115 of contact with said cross-bars 33 of the sprocket chains. This obviously has the effect especially at the point at which the film tape first passes over the sprockets, to throw a little more film upon the carrier 120 than exactly corresponds with the length of the latter, thereby providing sufficient slack in the film tape to prevent the same at any time buckling the carrier and thus possibly interfering with the smooth operation 130

of the device. The depth of the said grooves 36 is preferably very slightly in excess of the diameter of the said cross-bars 33 so that the excess of tape fed will be in-
5 sufficient to provide sufficient slack to permit the side edges of the same to pass over the apexes of the links 31, the latter obviously acting as guides for the side edges of said film tape.

10 It will be obvious, of course, that the sprocket chain or articulate carrier for carrying the film through the drying chamber may be continuous with the chain for passing the film through the tanks for treating
15 the same, but I have found that there is no advantage in so doing for the reason that the length of the film tape is such as to easily enable an operator to disconnect the forward end from the carrier for passing it through the tanks, then pass it over the
20 wiping devices above referred to, and then attach it to the carrier for passing the film through the drier without in any way interrupting the operation of the device or delaying the attachment of the second film
25 to the carrier as soon as the end of the first film has been taken up thereby. The total length of the chain for passing the film through the tanks is preferably considerably in excess of the greatest length of film to be
30 treated so that there will be a considerable interval elapsing between the attaching of the front end of one film to the carrier to be taken up thereby from a reel, and until
35 the forward end of the next preceding film will be delivered at the other end of this portion of the apparatus preparatory to its passage over the wiping devices and its attachment to the carrier for passing it
40 through the drier. The carrier in the latter is also preferably of considerably greater length than the greatest length of film tape to be treated so that there will be sufficient intervals for the operator to detach the front ends of films successively from the carrier in
45 the drier and start the same on the reel upon which such film is adapted to be wound.

In order to facilitate attachment and detachment of the film tape from the carriers
50 I preferably connect the forward end of the tape with the loop or link 41 engaged in the hook 42 at one end of a plate 43 made of relative thin sheet metal (preferably Monel metal). The latter is provided contiguous to one end thereof with a concavo-convex portion 44, the mouth of which is of very slightly less width than the diameter of the cross-bars 33 of the carrier, the latter being adapted to be sprung into
55 said concavo-convex portion 44 and be thus engaged therewith. This portion of the plate will easily pass over the sprockets 3 without causing the chain to be thrown out of engagement therewith, the convex portion being adapted to enter the grooves in

the sprockets. The lip 45 of said plate 43 is adapted to be engaged by the thumb as the links of the chain are grasped by the fingers to force said plate out of engagement with the chain. The loop 41 is preferably 70 elastic, and I have found that ordinary rubber bands are perfectly adapted to the purpose. The end of the film tape is folded over and pinned to form a loop through the rubber band or link 41 in a well-known 75 manner.

The film tape as it enters the drier is water soaked and expanded, and in drying it will shrink considerably so that as it progresses through the drying chamber it 80 will become gradually shorter in direct ratio to its loss of moisture. Such shortening or shrinkage will gradually cause the said film-tape to be placed under a tension and owing to the fact that the same is relatively strong and tough this action will cause it to lift the spools or drums 7 and will cause the portions of the chain between the same and the sprockets 3 to buckle. This is, of course, undesirable and may be avoided 85 by the operator watching the film rather carefully and changing the position of the attaching means or the point of attachment of the film to the chain or carrier at intervals to compensate for the shortening 90 or shrinkage thereof. As the operator can not always be at hand to watch this portion of the apparatus, it is preferable to provide means for automatically slackening the film. 95

While the film wiping device interposed 100 between the film treating and film drying portions of the apparatus constitutes no part of the present invention except in so far as it acts in unison and combination with said parts to deliver the finished film from the 105 apparatus, a brief description thereof will not be out of place.

Suitably rotatably supported in proximity to the sprockets of the film-treating portion of the apparatus is a padded roller 54 110 covered with chamois skin or buckskin or a similar material which will absorb water very easily and from which the water is easily wrung. It is well-known that this material when wet affords a very slippery and smooth surface which is non-abrasive and, therefore, will not scratch or mar the film surfaces coming in contact therewith. Associated with said roller 54 and held in yielding contact therewith in a suitable 115 manner by means of springs 55 is a roller 56 of metal or other suitable material, preferably hard and non-absorbent. The said roller 54 is rotated in the direction of travel of the film tape over the same, though this is not essential, and at very slow speed. During rotation thereof the said roller will take up the water from the film surface in contact therewith and the action of the metal roller 56 is such as to wring the water out of 120 125 130

the surface covering of the roller 54, thus rendering the surface of the latter sufficiently capable of absorbing all water that is delivered thereto by the film tape. The 5 film tape after being passed over the roller 54 is passed over a spool or drum 7 which may, if desired, be disposed in the bottom of a tank 57 containing glycerin or any other liquid which it may be desired to apply to 10 the film, though preferably this tank will receive only the water wrung from the said roller 54. After passing over the said spool or drum 7 in said tank the sensitized face of the film passes over a roller 58 similar to 15 the roller 54 and similarly having a metal roller 56 associated therewith, and passes then over an idle roll 59 and again over the said roller 54 at a point laterally of its first point of travel over the same; thus wiping 20 from the back of the film during the second passage any drops of moisture which may have dropped thereon from the wringing operation following its first passage over the said roller 54. The film then passes 25 over a large drum 60 also covered with material adapted to still further dry the back of the film and is then attached to the chain or carrier for passing said film tape through the drier.

30 In order to provide a maximum film treating capacity for a minimum of space, and also to economize on mechanism and labor, I preferably provide two of said film treating apparatuses parallel with each other, 35 the shafts 2 and the connection with source of power, etc., being common to both thereof. This arrangement renders possible running two complete film treating apparatuses with fifty per-cent. more labor than is required for one thereof.

The operation of the apparatus will be clearly understood from the foregoing description and the essence of the invention gathered therefrom; it being understood, of course, that the construction of the embodiment illustrated and described may be changed and varied at will to suit the particular purpose for which the device is to be employed without departing from such invention as defined in the appended claims.

In Figs. —6— and —7— I have illustrated a slightly different embodiment of the invention in which all of the tanks for liquids corresponding to the tanks 11—20 inclusive of Fig. —2— are separated from each other by substantially equal spaces, and in which the shafts carrying the sprockets over which the chain is trained extend only over one set instead of two parallel sets of 60 said tanks, it being obvious, of course, that such shafts may be extended as in Fig. —2— to extend over parallel rows of said tanks as will be obvious; the operation of this embodiment is exactly the same as that shown 65 in Fig. —2—, and further particular de-

scription thereof is, therefore, deemed superfluous.

The detail sectional view of the shaft, shown in Fig. —7— is the same in construction as the shafts employed in the structure 70 shown in Fig. —2—, the only difference being the particular form of bearing employed, but this detail may obviously be changed and varied at will without departing from the invention and, therefore, this sectional view 75 may be taken as exemplary of the construction of shaft and sprocket employed throughout.

The invention also comprehends the employment of means for raising all of the 80 shafts, sprockets and parts connected therewith out of the several tanks 11—20 inclusive and to this end the standards and cross-rods supporting the bearings for these several shafts carrying the sprocket chains are 85 adapted to be raised by any suitable gearing to an elevation sufficient to draw the idle drums or sprockets 7 from the upper ends of the tanks thereby enabling the latter to be removed from their normal positions for 90 purposes of cleansing, repair, etc., without interfering in any way with the mechanism for passing the film tape therethrough.

While I have omitted from particular illustration the means for filling and draining the various tanks it will be understood 95 of course, that these details are supplied upon the apparatus in actual use, though special description thereof has not been deemed necessary.

I claim as my invention:

1. In a film treating apparatus, a carrier for film tape consisting of a sprocket chain comprising articulate side portions comprising alternate links of different depth, and 105 cross-bars connecting the links of greater depth on opposite sides of the chain with each other and affording a foraminous support for the film tape, the pivotal connections between the links of said articulate 110 side portions being loosely made to permit free relative pivotal movement of said links and permitting lateral distortion of the structure, whereby the same may be twisted to form a helix.

2. In a film treating apparatus, a carrier for film tape consisting of a sprocket chain comprising articulate side portions comprising alternate links of different depth, the 120 said links of greater depth pivotally connected at opposite edges with the links of less depth, and cross-bars connecting the base portions of the deeper links in the opposed articulate members with each other, the horizontal planes intersecting said cross-bars, and the pivots of said links respectively being parallel and separated from each other by an appreciable space.

3. In a film treating apparatus, a carrier for film tape consisting of a sprocket chain 130

comprising articulate side portions comprising alternate links of different depth, the said links of greater depth pivotally connected at opposite edges with the links of less depth, and cross-bars connecting the base portions of the deeper links in the opposed articulate members with each other, the horizontal planes intersecting said cross-bars and the pivots of said links respectively, being parallel and separated from each other by an appreciable space, the plane of said cross-bars being disposed nearer adjacent the base edges of said deeper links than the plane of said pivots.

4. In a film treating apparatus, a carrier for film tape including a sprocket chain comprising parallel articulate structures connected together by means of parallel cross-bars at intervals, and sprockets engaging said cross-bars to impart movement to said chain, the grooves of said sprockets receiving said cross-bars being of greater depth than the diameters of the latter whereby to cause the faces of said sprockets to throw the film-tape carried by said cross-bars out of engagement with the latter as the same enter said grooves.

5. In a film treating apparatus, a carrier for film tape including a sprocket chain comprising parallel articulate structures connected together by means of parallel cross-bars at intervals, and sprockets engaging said cross-bars between said articulate structures to impart movement to said chain, the grooves of said sprockets receiving said cross-bars being of greater depth than the diameters of the latter whereby to cause the faces of said sprockets to throw the film-tape carried by said cross-bars out of engagement with the latter as the same enter said grooves, there being annular grooves in said sprockets communicating with said longitudinal grooves and adapted to receive said articulate members.

6. In a film treating apparatus, film feeding means including a plurality of parallel driven shafts each carrying a plurality of sprockets, an articulate film carrier trained successively over the several sprockets on each shaft, and an idle roll asso-

ciated with each two adjacent sprockets of each shaft and each suspended in a loop of the carrier.

7. In a film treating apparatus, film feeding means including a plurality of parallel driven shafts each carrying a plurality of sprockets, an articulate film carrier trained successively over the several sprockets on each shaft, and an idle roll associated with each two adjacent sprockets of each shaft and each suspended in a loop of the carrier, said carrier adapted to maintain one face of the film tape carried thereby opposed at all times to the faces of the sprockets and idle rolls.

8. A film treating apparatus including a series of parallel horizontal shafts adapted to be simultaneously rotated at uniform speed, a plurality of sprockets of equal pitch-diameters on each of said shafts, an articulate carrier for film tape trained successively over all of said sprockets or said shafts from end to end of the same, and thence over all of the sprockets of the next succeeding shaft in the opposite direction, idle rolls alternating with the sprockets of each shaft and suspended in loops of said carrier depending from two of the sprockets of each shaft for maintaining said carrier taut and engaged with said sprockets.

9. In a film treating apparatus, a plurality of shafts each carrying a plurality of sprockets, all of said shafts being parallel and adapted to be driven simultaneously at uniform speed and all of said sprockets on said shafts being of equal pitch diameter, an articulate carrier trained successively over all of the sprockets of each shaft consecutively, and idle rolls suspended in loops of the carrier depending from said sprockets, said idle rolls alternating with the sprockets of each shaft over which said carrier is trained.

In testimony whereof I have signed my name in presence of two subscribing witnesses.

FREDRICK B. THOMPSON.
